UNITED STATES PATENT OFFICE

ANDREAS RÜGAMER, OF PFORZHEIM, GERMANY

HYGIENIC DENTAL BURR-CLEANING APPARATUS

Application filed October 22, 1927, Serial No. 228,067, and in Germany January 3, 1927.

This invention relates to a new and useful apparatus for cleaning dental burrs; and its primary object is, to provide a device which is adapted to free the used burrs from the adhering foreign matter by mechanical means and deposit the removed bacteria carrying matter within a receptacle which envelops the cleaning brush.

I attain this object by the mechanism illustrated in the accompanying drawings, showing the preferred form of my invention and in which

Fig. 1 is a side elevation of the apparatus, Fig. 2 a front elevation of the apparatus, Fig. 15 3 a plan view of the apparatus, and Fig. 4 an elevation of the left hand side of the casing shown in Fig. 2.

Similar letters refer to similar parts throughout the several views.

20 The apparatus consists essentially of the standard *u* which can be clamped to a table, the drum *w*, mounted on the bolt *v* and provided with axially extending grooves on its periphery, the worm-gear *x*, *y*, for rotating said drum, the brake-block *z* disposed above the drum *w*, the circular brush *e* having the toothed drive *c*, *d'*, *d*, of the burr support plate *f* and the sheet metal casing *a* enclosing the brush *e*.

30 The burrs *f'* to be cleaned, are placed upon the plate *f* (Fig. 2) on the left side of the apparatus, where they lie against the drum *w* in consequence of the inclined position of the plate *f*. By rotating the crank *b* provided on pinion *c*, the brush *e* is rotated by means of the gear-wheels *c*, *d'*, *d*, on the one hand, and the drum *w* by means of the worm-gear *x*, *y*, on the other hand, the brush quickly and the drum slowly. Upon rotation

40 of the drum, the burrs lying on the plate *f* are taken up one after the other by the grooves of the drum *w* and passed by the rotating cleaning brush *e*, the burrs themselves being rotated about their longitudinal axes by friction against the brake-block *z*, advantageously consisting of rubber, so that all the teeth of the burrs are engaged by the brush. When the burrs have passed the brush and therefore also the brake-block *z*, they fall out of the grooves of the drum *w*

into the chute *o'* from which they slide out of the apparatus.

With regard to the inclined position of the teeth in the burr-head and in order that the bristles of the brush may act in the direction of the grooves of the teeth, the brush shaft *s* is inclined to the longitudinal axes of the burrs.

The brush *e* is enclosed from outside by the sheet-metal casing *a* which serves to catch the matter flung from the brush. Said casing is clamped to the apparatus by the screw *b'* which fits into the slotted projecting lap *a'* of the casing *a* and can be readily removed after loosening said screw.

By means of a small opening *a''* at the top of the casing *a* other instruments, as for example nerve-needles, can be cleaned on the brush *e*.

As will be evident to those skilled in the art, my invention permits of various modifications without departing from the spirit thereof or the scope of the appended claims.

What I claim is:

A dental burr cleaning apparatus, comprising in combination, a cleaning brush journaled in a casing, a rest for the burrs to be cleaned, means to engage the burrs from their rest and feed them to said brush and means to rotate the burrs about their longitudinal axes when passing by the brush.

In testimony whereof I have hereunto subscribed my name.

ANDREAS RÜGAMER.
